DESIGN FOR A TOY CANNON

Henry J. Nycz, Milwaukee, Wis.

Application September 23, 1936, Serial No. 64,983

Term of patent 3½ years

To all whom it may concern:

Be it known that I, Henry J. Nycz, a citizen of the United States, residing at Milwaukee, in the county of Milwaukee and State of Wisconsin, have invented a new, original, and ornamental Design for a Toy Cannon, of which the following is a specification, reference being had to the accompanying drawing, forming part thereof.

In the drawing:

Fig. 1 is a side elevational view of the toy cannon showing my new design; and

Fig. 2 is a plan view thereof.

I claim:

The ornamental design for a toy cannon, substantially as shown.

HENRY J. NYCZ.
